JULIAN F. PINTO, OF SACRAMENTO, CALIFORNIA, ASSIGNOR OF ONE-HALF TO W. B. JENKINS, OF SACRAMENTO, CALIFORNIA

ELASTIC SUPPORTER AND CLASP

Application filed April 12, 1932. Serial No. 604,809.

This invention relates to certain new and useful improvements in elastic supporters and clasps.

The primary object of the invention is to provide an elastic supporter and clasp, especially designed for the support of hose or the like, the clasp being of a type adaptable for use on belts, suspenders etc., and securely retaining the strap element associated therewith in adjusted position.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is an elevational view of an elastic supporter and clasp constructed in accordance with the present invention;

Figure 2 is an elevational view of the clasp with the cover in open position with a folded section of the elastic or strap overlying the base portion of the clasp;

Figure 3 is a plan view, similar to Figure 2, showing the strap portion removed from between the clasp section and illustrating the sliding lock for the clasp;

Figure 4 is a rear elevational view of the clasp with the elastic or strap in position therein;

Figure 5 is a top plan view of the clasp in closed position with the elastic or strap disengaged therefrom;

Figure 6 is an edge elevational view of the clasp showing the teeth or prongs on an edge of a clasp wall to be engaged with the elastic or strap;

Figure 7 is a detail sectional view taken on line 7—7 of Figure 1;

Figure 8 is a detail sectional view taken on line 8—8 of Figure 1;

Figure 9 is a cross-sectional view taken on line 9—9 of Figure 1 showing the grooved or notched end of the clasp cover to receive the hook end of the sliding lock; and

Figure 10 is an edge elevational view of the elastic supporter and clasp illustrating an

other form of attachment for the supporting strap.

Referring more in detail to the accompanying drawing, there is illustrated an elastic supporter and clasp of the type usually employed by women for the support of hose and wherein the supporter is attached to a corset or other garment, it being understood however that the device may be used for other purposes, such as the support of a brassière or the like, the clasp being associated with a supporting strap in a manner to permit length adjustment of the supporting strap, said clasp being formed of a base section 15 provided with side edge flanges 16 and having a cover 17 hinged thereto at one end as at 18, the cover 17 carrying a single side flange 19 and an outer end flange 20 to be moved into binding engagement with the supporting strap when the cover 17 is folded upon the base section 15. As shown in Figure 3, the inner face of the cover 17 carries pin or prong projections 21 that bite into the supporting strap and one of the edge flanges 16 of the base 15 carries upstanding prongs 22 that bite into the supporting strap to hold the latter against movement when the clasp cover is in its closed position.

The devices for holding the cover 17 in closed position include a slide arm 23 mounted in upstanding guide loops 24 struck out from the base 15 in a direction toward the cover 17 as shown in Figure 3, end fingers 25 projecting laterally of the inner end of the slide arm 23 limiting outward movement of the slide arm. The outer end of the slide arm 23 is provided with a reversely bent finger grip or hook 26 that is received in a depressed portion 27 in the upper side of the outer end of the cover 17 so that the finger grip 26 lies in the same plane as the cover 17 for the elimination of any parts projecting from the clasp. To open the clasp, the finger grip 26 is engaged to slide the arm 23 and free the finger grip from the depressed portion 27 in the cover, whereupon the latter may be swung to its open position upon its hinge mounting 18 as illustrated in Figures 2 and 3.

One side edge of the base 16 of the clasp is longitudinally slotted as at 28 through

which one end of a supporting strap 29 is passed and anchored as by stitching or the like as at 30. The strap 29 is then passed through one side loop of a double link 31 5 and re-directed between the clasp base and cover 17, the free end of the supporting strap 29 being secured as by stitching or the like as indicated by the reference numeral 32 to one bar of a safety pin or other fastening device 10 vice 33 that is employed for attaching the supporter to a corset or other garment. The length of the supporting strap 29 is varied by releasing the cover 17 in a manner as previously described and moving the strap through 15 the double link 31, the cover 17 of the clasp when in closed position being securely retained by the slide arm 23 while the supporting strap 29 is restrained against slipping movement by the prongs 21 and 22 as well as 20 the cooperating flanges on the edges of the clasp base and cover.

The hose supporting straps 34 are associated with the other loop of the double link 31 and each hose supporting strap carries a 25 garter clasp 35 or other device for attachment to hose or other garment to be supported in position.

In the use of the supporter and clasp as illustrated in Figure 10, a link member 36 is 30 attached to the garment 37 and the use of the pin fastener 33 illustrated in Figure 1 is eliminated, the supporting strap 29a extending from the clasp 15 threads through the double link 31 and link 36 upon the garment 35 with the free end 29b of the supporting strap 29a confined between the sections of the clasp. In this form, the link member 36 is permanently attached to the garment and the supporting strap 29a is adapted to be engaged 40 therewith.

From the above detailed description of the invention, it is believed that the construction and operation thereof will at once be apparent and while there are herein shown and described the preferred embodiments of the invention, it is nevertheless to be understood that minor changes may be made therein without departing from the spirit and scope of the invention as claimed.

50 I claim:—

1. In an elastic supporter and clasp, a clasp comprising a base plate, a cover hinged thereto, a slide arm carried by the base plate and a hook on one end of the slide arm engageable with the cover to retain the same in closed position, and said cover having a depression therein to receive the hook with the latter lying in the same plane as the cover.

2. In an elastic supporter and clasp, a 60 clasp comprising a base plate, a cover hinged thereto, a slide arm carried by the base plate and a hook on one end of the slide arm engageable with the cover to retain the same in closed position, the connection between the base plate and slide arm including guide

loops struck-out of the base plate beneath which the arm is mounted and bent fingers on the arm to limit outward sliding movement of the arm.

3. In an elastic supporter and clasp, a 70 clasp comprising a base plate, a cover hinged thereto, a slide arm carried by the base plate and a hook on one end of the slide arm engageable with the cover to retain the same in closed position, said cover having a depression therein to receive the hook with the latter lying in the same plane as the cover, the connection between the base plate and slide arm including guide loops struck-out of the base plate beneath which the arm is mounted and bent fingers on the arm to limit outward sliding movement of the arm. 75

4. In an elastic supporter and clasp, a 80 clasp comprising a base plate, a cover hinged thereto, a slide arm carried by the base plate and a hook on one end of the slide arm engageable with the cover to retain the same in closed position, the connection between the base plate and slide arm including guide loops struck-out of the base plate beneath which the arm is mounted and bent fingers on the arm to limit outward sliding movement of the arm. 85

5. In an elastic supporter and clasp, a 90 supported strap attached to one side of the base plate, a link through which the strap passes with the intermediate portion of the strap confined between the base plate and cover, garment attachment means carried by the free end of the strap, and garment supporters carried by the link.

5. In an elastic supporter and clasp, a 95 clasp comprising a base plate, a cover hinged thereto, a slide arm carried by the base plate and a hook on one end of the slide arm engageable with the cover to retain the same in closed position, said cover having a depression therein to receive the hook with the latter lying in the same plane as the cover, the connection between the base plate and slide arm including guide loops struck-out of the base plate beneath which the arm is mounted and bent fingers on the arm to limit outward sliding movement of the arm, a supporting strap attached to one side of the base plate, a link through which the strap passes with the intermediate portion of the strap confined between the base plate and cover, garment attachment means carried by the free end of the strap, and garment supporters carried by the link. 100

6. In an elastic supporter and clasp, a 105 clasp comprising a base plate, a cover hinged thereto, a slide arm carried by the base plate and a hook on one end of the slide arm engageable with the cover to retain the same in closed position, the connection between the base plate and slide arm including guide loops struck-out of the base plate beneath which the arm is mounted and bent fingers on the arm to limit outward sliding movement of the arm, a supporting strap attached to one side of the base plate, a link through which the strap passes with the intermediate portion of the strap confined between the base plate and cover, garment attachment means carried by the free end of the strap, and garment supporters carried by the link. 110

6. In an elastic supporter and clasp, a 115 clasp comprising a base plate, a cover hinged thereto, a slide arm carried by the base plate and a hook on one end of the slide arm engageable with the cover to retain the same in closed position, the connection between the base plate and slide arm including guide loops struck-out of the base plate beneath which the arm is mounted and bent fingers on the arm to limit outward sliding movement of the arm, and opposed strap engag- 120

ing prongs carried by the base plate and cover.

7. In an elastic supporter and clasp, a clasp comprising a base plate, a cover hinged thereto, a slide arm carried by the base plate and a hook on one end of the slide arm engageable with the cover to retain the same in closed position, said cover having a depression therein to receive the hook with the latter lying in the same plane as the cover, the connection between the base plate and slide arm including guide loops struck-out of the base plate beneath which the arm is mounted and bent fingers on the arm to limit outward sliding movement of the arm, and opposed strap engaging prongs carried by the base plate and cover.

In testimony whereof I affix my signature.
JULIAN F. PINTO.
